Primary Examiner — Paula Allen Greene(57) **CLAIM**

The ornamental design for a base cradle for a communications headset, as shown and described.

DESCRIPTION

FIG. 1 is a front-right perspective view of a base cradle for a communications headset showing my new design;
FIG. 2 is a back-top-left perspective view thereof;
FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

In the drawings, the claimed design is defined by the shaded surfaces.

The broken lines shown in dot-dot form depict environment and form no part of the claimed design.

The broken lines shown in dot-dash form assist to depict the scope or bounds of the claimed design.

The remaining broken lines are shading or contour lines and are not actually visible on the surface.
